[57] CLAIM

The ornamental design for a base for a magnetic machine tool, as shown and described.

DESCRIPTION

FIG. 1 is a perspective view of a base for a machine tool showing our new design;

FIG. 2 is an enlarged left side elevational view thereof, the drill being shown in broken lines for illustrative purposes only;

FIG. 3 is an enlarged right side elevational view thereof;

FIG. 4 is an enlarged front elevational view thereof;

FIG. 5 is an enlarged rear elevational view thereof;

FIG. 6 is an enlarged top plan view thereof;

FIG. 7 is an enlarged bottom plan view thereof.

FIG. 1

FIG. 2

FIG. 3

FIG. 4FIG. 5FIG. 6

FIG. 7
